 tion of New York

Application January 13, 1947, Serial No. 721,679

4 Claims. (Cl. 209—463)

1

The method and apparatus which I have invented is for separating materials which have different settling rates in liquid such as water; for instance, iron ore which contains materials of varying density such as silica and iron oxide. In free settling through water, the particles which will settle to the bottom of any container first may be smaller particles of the heavier material which will arrive at the bottom of any given container before even larger particles of a lighter material. Where the material is composed of particles all of which are homogeneous, the size is ordinarily the determining factor in the rate of settling. It is to be understood that this invention relates to the separation of particles of different rates of settling.

In general, my process and apparatus consists in employing a moving surface, or platform, underneath a liquid. Onto the moving surface is dumped, or fed, unsized pulp. The fines in the pulp remains in suspension and the coarse particles rest on the moving platform. Because the moving platform has a motion in the liquid, for instance water, the fines are tended to be dislodged from the coarse particles by reason of the washing action of the water on the coarse particles after they rest on the platform. Thus there is a continual washing action which tends to maintain the fines in suspension, and the eddy currents created by the motion of the deposited material on the moving platform under the liquid keeps the fines from settling, and even causes them to be brought again into suspension after they have started to settle.

This type of classifier may be used with grinding mills in accordance with common practice.

The unsized pulp is fed to my classifier at the influent end a reasonable distance away from the fines overflow point. The coarse particles may be sent again to the mill to be reduced in size and may be re-fed to the classifier. It is obvious that a change in speed of the moving platform will also affect the fines discharge. At very low speeds, the moving platform will cause negligible disturbance near the bottom with the result that fines in addition to the coarse particles once deposited on the platform will tend to remain there and be carried up with the pre-settled coarse particles to the discharge. The faster the movement of the platform the greater is the agitation adjacent to it, and the greater the tendency to keep the finer particles in suspension. If finer particles of a given size cannot remain on the moving surface without being washed off, they will stay in suspension and become part of the

2

fluid medium, with the result that when a sufficient number are present in the fluid medium they will flow as fines over the overflow end of the classifier with the liquid.

5 The action and principles of this moving platform classifier are radically different from other types that scrape the solids by rakes, drags, or screw flights over a stationary surface. In these types coarse and fines are mixed together, or fines are drained through the coarse, thus holding them in the mass. The principle of depositing the unsized pulp on the moving submerged surface permits the fines next settling on the moving surface to be washed back into the liquid where they can be delivered to the fines discharge point. The scraper which I employ to remove the particles deposited on the moving platform has in itself a squeezing action on the deposited particles, and liquid and fines are forced out. Thus the material on the platform gets an additional desliming as well as a dewatering action.

In the drawings:

Fig. 1 is a vertical cross sectional view, taken along the line 1—1 of Fig. 2 looking in the direction of the arrows, of a simple form of my system employing a horizontal rotating disc.

Fig. 2 is a top plan view of the device shown in Fig. 1.

Fig. 3 is a vertical cross sectional view of a modification of the device shown in Figs. 1 and 2, taken along the line 3—3 of Fig. 4 looking in the direction of the arrows.

Fig. 4 is a top plan view of the form of invention shown in Fig. 3.

35 Fig. 5 is a vertical cross sectional view of a form of my device employing a moving belt horizontally suspended in liquid, taken along the line 5—5 of Fig. 6 looking in the direction of the arrows.

Fig. 6 is a top plan view of the device shown in Fig. 5.

Fig. 7 is a vertical sectional view of a modification of the device shown in Figs. 5 and 6, taken along the line 7—7 of Fig. 8 looking in the direction of the arrows.

45 Fig. 8 is a top plan view of the device shown in Fig. 7.

Fig. 9 is a top plan view of another form of device using a moving belt.

50 Fig. 10 is a sectional view of a form of the device shown in Fig. 9 taken along the line 10—10 of Fig. 9 looking in the direction of the arrows.

Referring to the drawings, I have shown a tank 1 which is circular in configuration and provided with a fines overflow discharge chute 2. Adapted

3

to rotate near a bottom 3 of the tank 1 is a disc 4 suspended on a shaft 5 which is driven by suitable gearing 6 connected to a source of power, not shown. The shaft 5 is restricted in diameter as illustrated at 7 where it passes through the disc 4 and a holding nut 8, or other similar holding member, holds the disc 4 on the shaft 5 so that it is rotated with the shaft 5.

Unsized pulp is fed through a duct 9 onto the surface of the disc 4 which is rotated under the surface of water 10 in the tank 1. The tank 1 is provided with a collecting trough 11 at one end, in which is mounted a conveyor screw 12 driven by a source of power, not shown, which is adapted to deliver the coarse washed sands to a coarse sands discharge outlet 13.

Adapted to scrape the coarse particles 14 from the disc 4 is a scraper member 15. It has been found that the scraper 15 should be set at enough of an angle to the direction of motion of the coarse particles to scrape them off without permitting them to be piled up to too great an extent adjacent the scraper. In other words, the angle of the scraper, it has been found, should be set so as to feed the coarse particles with comparative ease into the discharge chute 11.

Referring to the drawings, Figs. 1 and 2, it will be seen that the unsized pulp is fed through the feed pipe 9 onto the rotating disc 4, and falls through the water 10 onto the disc. While falling through the water, the fines become suspended in the water. The coarse particles after they near the upper surface of the rotating disc 4, and when they touch the rotating disc 4, are subjected to eddy currents which wash out more of the fines. These fines in suspension pass over the fines overflow 2. The coarse particles on the disc 4 are subjected to a washing action of the water during the rotation of the disc until they reach a point adjacent the scraper 15, at which point they are scraped off into the discharge chute 11. The material scraped off the disc 4 falls into the bottom of the chute, and is fed by the conveyor screw 12 to the coarse sands discharge point 13. Here the coarse particles can be sent again to the mill and re-fed through the unsized pulp feed pipe 9 for re-processing.

The great efficiency of my system is in part due to the eddy currents adjacent the surface of the disc. The coarse particles as they approach the disc 4 are subjected to a washing because of these eddy currents which loosens the fines and tends to keep them in suspension. Moreover, the particles after they rest on the upper surface of the disc 4 are subjected to eddy currents and washing as the deposited particles move along with the rotating disc. This tends to remove the fines from the coarse particles and causes a very efficient operation of the classifier.

The coarse particles and the fines are not mixed together and the fines are not drained through the coarse, thus holding them in the mass, as has been the case with other classifier systems. It is to be emphasized that the movement of the rotating platform causes the fines to be washed back into the liquid zone. Moreover, the action of the scraper 15 is to squeeze the fines and the water out of the coarse particles, just at the point that the coarse particles are discharged from the classifier.

The greater the speed of rotation of the disc the greater the washing action of the water. It is to be noted that there is greater washing action near the periphery of the disc 4 than near the center, because of the greater speed of travel of

4

points near the periphery than of points near the center.

Now referring to Figs. 3 and 4, a somewhat similar arrangement is shown. Here the tank 1 is provided with an upwardly sloping bottom 16 and the disc 4 is arranged to rotate parallel to the bottom 16. The scraper 15 is set so as to scrape the higher side of the disc 4. The disc 4 is arranged so that its higher side during its rotation continually emerges above the surface of the liquid 10, and there is a high portion of the disc 4 which I have indicated by the numeral 17 which lies without the water.

It is at this point that I preferably arrange to scrape, by means of scraper 15, the coarse sands into a coarse sands discharge chute 18. Though I have shown the discharge position of the settled solids, as above the surface of the liquid they could be under the liquid, but at a higher point than the lower point of the disc. The liquid adjacent the disc in either case tends to rotate with the disc and the solids on the disc, but eddy currents are produced in the liquid. Where the discharge is above the surface of the water, some water is carried above the surface of the liquid and washes back, carrying with it those fines which are lightly resting on the disc or on the coarse particles on the disc. The liquid velocity at this point will carry them back and not permit them to be discharged with the more tenacious portion of the load which is the heavier coarser sizes. The result of this action, particularly where the discharge is above the surface of the liquid, is that the fines will remain in suspension in the tank and they will be built up to a degree where they tend to remain in suspension, and eventually will go over as fines at the overflow 2.

Now referring to Figs. 5 and 6, I have shown a form of device in which I use a rectangular tank 20 in which is adapted to rotate a belt 21 mounted on suspending rollers 22, driven by some suitable source of power, not shown. The belt 21 is adapted to move in the direction of the arrows in a liquid 23 with which the tank 20 is filled. The belt 21 and the belts shown in the succeeding forms of the invention are preferably substantially impervious. The tank 20 is provided with a fines overflow 24 and a discharge chute 25, in which latter is adapted to move a discharge belt 26 mounted on rollers 27, driven by some suitable source of power, not shown. Adjacent one of the rollers 22 where the particles of the pulp tend to collect, as shown at 28, I have shown a scraper 29 to prevent the particles of the pulp from passing between the roller 22 and the belt. A similar scraper 29, for the same purpose, is shown adjacent one of the rollers 27 over which the discharge belt rotates.

In operation the unsized pulp is fed to the classifier through the feed 9 and falls on the upper surface of the moving belt 21. I have shown the feed pipe 9 as located approximately halfway down the length of the belt 21, but it might be located further, for instance, toward the end of the trough 20 nearer the fines overflow discharge outlet 24.

Here again the action of the moving platform formed by the belt 21 is somewhat similar to that brought about by the moving disc 4 of the form of the invention described in connection with Figs. 1 to 4 inclusive. Eddy currents are formed adjacent the belt 21 which tend to prevent the fines from settling and staying on the surface 75 of the belt 21 with the coarse particles. The

belt 21 feeds the coarse particles which remain on the belt over the end of the belt as indicated by the arrow, see Fig. 5, onto an elevator belt 26 where the particles move forward and over the top end of the belt 26 where it passes over one of rollers 27, and discharges the coarse particles as shown by the arrow at the upper right-hand of the drawing, Fig. 5. There is a washing action of the coarse particles on the belt 26 particularly where the belt 26 passes out of the water, since some of the water is entrained with particles on the surface of the belt 26, and tends to wash the fines out of the coarse particles.

The coarse particles which are discharged from the belt 26 can go back to the mill and can be reduced in size and again fed back to the classifier.

The form of device shown in Figs. 7 and 8 is one in which a single belt is employed. Here the trough 20 is provided with a discharge chute 30. There is a single belt 31 which is adapted to travel from a low point 32 in the tank 20 to a high point 33 and the coarse particles on the belt 31 are adapted to be discharged as indicated by the arrow into a discharge outlet 34. The belt 31 is adapted to travel on rollers 35 and 36 driven by some suitable source of power, not shown, and the belt 31 may be long enough to have a sag in it, as indicated at 37.

I have shown a scraper 38 which is adapted to scrape material which has settled on the upper surface of the lower belt section of belt 31 to prevent its passing under the roller 35, and between the roller 35 and the belt 31.

Here there is a definite washing action as the belt 31 passes above the surface of the water 23 in the tank 20. The water which is carried forward with the belt above the surface of the water in the tank 20 washes back into the tank and takes with it fines. So here we again have the washing action as the moving platform, which in this case is the belt, passes above the surface of the liquid in the tank. This washing action is in addition to the eddy currents which act upon the particles by reason of the motion of the belt through the liquid.

The form of device shown in Figs. 9 and 10 is one employing a moving belt 40 which is adapted to pass over rollers 41, 42 and 43. Power may be applied to any of these rollers, for instance the roller 41, so that the belt 40 is adapted to move in the direction of the arrows. The unsized pulp is designed to be fed through a duct 9 onto the surface of the belt 40, as indicated in Fig. 10. The surface of the belt 40 lies below the surface 44 of a body of liquid 45 in a tank 46. There is provided in the tank 46, in which the body of water 45 is contained, an overflow launder 47 through which is discharged liquid containing the fines. The liquid containing the fines flows into the overflow launder 47, as indicated by the arrows in Fig. 10.

The belt 40, which is preferably impervious as are all the belts in the forms of the invention shown in this application for patent, is provided with scrapers 48 which are adapted to dislodge and agitate the particles which tend to accumulate underneath the belt 40 at the lower end 49 of the tank 46. The belt is nearly horizontal at this point, though later it rises in an upwardly sloping section and passes out of the liquid 45. The roller 43 is provided with a scraper 50 which prevents material from collecting on the surface of the belt 40 which passes under the roller 43. Likewise, the surface of the roller 43 itself is

adapted to be kept free of deposited material by the scraper 50. If roller 43 is made sufficiently large to keep the top portion of the belt 40 substantially above the liquid in the tank 46, roller 42 and scraper 50 may be eliminated.

At the opposite end of the tank 46 from the overflow launder 47 is a discharge launder 51 through which is adapted to be discharged the coarse particles, which may be returned to the mill to be further ground and then again returned, if desired, to the classifier. The overflow launder 51 has mounted adjacent thereto a scraper 52 which lies adjacent the upper surface of the belt 40 as it passes out of the liquid 45.

In action the coarser particles tend to settle on the belt 40 as they pass along adjacent the bottom of the tank 46 on the belt 40. Here the movement of the belt 40 tends to wash out the fine particles from the mass as it tends to settle on the belt 40. As the coarser particles pass above the surface 44 of the liquid near the discharge launder 51 for the coarse particles, the entrained liquid washes the coarse particles on the belt 40 and tends to loosen the fines which may have been deposited on these coarse particles, and causes these fines to enter into suspension in the liquid 45. Moreover, there is a squeezing action due to the action of the scraper 52 which tends to wash the fine particles free from the coarse particles as the material is scraped off the belt 40 and passes out through the discharge launder 51. Instead of the scraper 52, a jet or jets, not shown, of liquid may be employed to wash the coarse particles from the belt 40, into the launder 51.

By my apparatus and method I have avoided washing the fines through the coarse particles and I also tend to prevent the mixing of the fines and coarse particles to a greater extent than is possible by the usual scraping with rakes, or employing drags or screw flights over a stationary surface.

While I have shown certain forms of my invention, it is to be understood that my invention is susceptible of variations in constructions and operation without exceeding the scope of the appended claims.

I claim:

1. A method of classifying particles which settle in a body of liquid according to differences in the settling rates of the particles comprising introducing a mixture of particles of different settling rates into a relatively quiescent body of liquid having an upper zone free from a positive classifying current, whereby the particles fall freely downward through the relatively quiescent zone of liquid, maintaining a path of withdrawal movement for settled particles through the liquid body along a moving surface which intercepts the line of fall of the particles intermediate the depth of the liquid body but sufficiently below the level of particle introduction to effect an initial classification of the falling particles in accordance with the existing settling rates thereof in relatively quiescent liquid, supporting and moving the particles which settle to said surface with the same and away from the line of particle fall at a velocity inducing a positive classifying turbulence in and surrounding said path which is uniform along any line taken across the path and parallel thereto, to effect an additional classification of particles adjacent said path which is uniform along any line taken across said path and parallel thereto, and controlling the speed of the said

moving surface to obtain the desired classification.

2. A method of classifying particles which settle in a body of liquid according to differences in the settling rates of the particles comprising introducing a mixture of particles of different settling rates into a relatively quiescent body of liquid having an upper zone free from a positive classifying current, whereby the particles fall freely downward through the relatively quiescent zone of liquid, maintaining a path of withdrawal movement for settled particles through the liquid body along a substantially plane and moving surface which intercepts the line of fall of the particles intermediate the depth of the liquid body but sufficiently below the level of particle introduction to effect an initial classification of the falling particles in accordance with the existing settling rates thereof in relatively quiescent liquid, supporting and moving the particles which settle to said surface with the same and away from the line of particle fall at a velocity inducing a positive classifying turbulence in and surrounding said path which is uniform along any line taken across the path and parallel thereto, to effect an additional classification of particles adjacent said path which is uniform along any line taken across said path and parallel thereto, controlling the speed of the said moving surface to obtain the desired classification, removing particles which remain settled in said path from the liquid body at one point, and removing particles in suspension in the liquid body together with liquid at another point.

3. A method of classifying particles which settle in a body of liquid according to differences in the settling rates of the particles comprising introducing a mixture of particles of different settling rates into a relatively quiescent body of liquid having an upper zone free from a positive classifying current, whereby the particles fall freely downward through the relatively quiescent zone of liquid, maintaining a path of withdrawal movement for settled particles through the liquid body along a substantially plane and moving surface which intercepts the line of fall of the particles intermediate the depth of the liquid body but sufficiently below the level of particle introduction to effect an initial classification of the falling particles in accordance with the existing settling rates thereof in relatively quiescent liquid, supporting and moving the particles which settle to said surface with the same and away from the line of particle fall at a velocity inducing a positive classifying turbulence in and surrounding said path which is uniform along any line taken across the path and parallel thereto, to effect an additional classification of particles adjacent said path which is uniform along any line taken across said path and parallel thereto, controlling the speed of the said moving surface

to obtain the desired classification, removing particles which remain settled in said path from the liquid body at one point, removing particles in suspension in the liquid body together with liquid at another point, and subjecting the particles remaining settled in said path to a de-sliming squeezing action adjacent the point of removal thereof from the liquid body.

4. A method of classifying particles which settle in a body of liquid according to differences in the settling rates of the particles comprising introducing a mixture of particles of different settling rates into a relatively quiescent body of liquid having an upper zone free from a positive classifying current, whereby the particles fall freely downward through the relatively quiescent zone of liquid, maintaining a path of withdrawal movement for settled particles through the liquid body along a substantially plane and moving surface which intercepts the line of fall of the particles intermediate the depth of the liquid body but sufficiently below the level of particle introduction to effect an initial classification of the falling particles in accordance with the existing settling rates thereof in relatively quiescent liquid, supporting and moving the particles which settle to said surface with the same and away from the line of particle fall at a velocity inducing a positive classifying turbulence in and surrounding said path which is uniform along any line taken across the path and parallel thereto, to effect an additional classification of particles adjacent said path which is uniform along any line taken across said path and parallel thereto, controlling the speed of the said moving surface to obtain the desired classification, and moving the particles which remain settled in said path and the particles in suspension in the liquid body along parallel paths to different discharge points.
